UNITED STATES PATENT OFFICE

FRANKLIN GRIMM, OF MORA, MINNESOTA

RURAL MAIL BOX

Application filed March 25, 1931. Serial No. 525,241.

This invention relates to an improved rural mailbox characterized by an arrangement of mechanical parts especially selected and correlated to provide a structure which is systematic and efficient in operation, and intended as a novel contribution to this particular line of endeavor.

5 The improvement resides in the use of a special compartment formed in the bottom of the box proper, said compartment serving to accommodate a slideable drawer and said drawer being designed to accommodate the mail, parcels, and coins.

10 A feature of the invention is predicated upon a drawer provided at its front with a hingedly mounted coin receptacle designed to facilitate removal of the coins by the mailman.

15 A second feature of the invention is found 20 ed on an arrangement which embodies operating connection between the slideable drawer and the hingedly mounted front doors constituting the closure means for the box, together with operating means for the drawer 25 er so that as the drawer is pulled out to exposed position, the doors are simultaneously swung open and vice versa.

30 The specific details and relative arrangement and association thereof and the complete structure will become more readily apparent from the following detailed description, the accompanying drawings, and the concluding claims:

In the drawings:

35 Figure 1 is a horizontal sectional view showing the complete arrangement with the doors open and the drawer extended to useful position.

40 Figure 2 is a view like Figure 1 showing the parts retracted.

Figure 3 is a front elevational view of Figure 1.

Figure 4 is a front elevation of Figure 2.

45 Figure 5 is a fragmentary longitudinal sectional view through the structure seen in Figure 1.

Figure 6 is a partial vertical sectional view through the box and through the front part 50 of the drawer.

Figure 7 is a perspective view of the drawer.

Figure 8 is a detail section on the line 8-8 of Figure 4.

In the drawings, in Figure 3 for example, 65 the numeral 9 designates generally the body portion of the box. This is of suitable proportions for convenient rural mail delivery service. It is of general vertically elongated rectangular configuration and formed with a 60 V-shaped top or roof 10.

At the front portion are outstanding flanges 11 on which companion flanges 12, which are offset, of the doors, are hingedly mounted as at 13. This allows the doors to 63 telescope slightly into the frontal portion of the box and to provide a nice joint. In fact, it will be observed that the upper edges of the doors are provided with weather excluding channels 14 which take over the edge portions 70 of the roof 10. Thus, the box itself is substantially weatherproof.

75 The insert 15 at the bottom of the box forms the base and it co-operates with the horizontal partition plate 16 in defining a longitudinally elongated horizontally extending compartment to receive the sliding parts of the mechanism. This compartment may well be distinguished by the numeral 17. The principal part of the aforesaid mechanism is the sliding 80 mail receiving and delivering drawer 18.

This is in the nature of a shallow pan and provided at its front with a small receptacle 19 hingedly mounted as at 20 and designed to contain coins. This hinge mounting allows 85 the receptacle to be lifted outwardly and inverted to drop the coins conveniently into the hand of the mailman.

90 The numeral 21 in Figure 7 merely designates a package or parcel retaining clip, whereas the numeral 22 indicates the centralized forwardly extending operating lever or handle terminating in a finger ring 23. The drawer is somewhat smaller than the compartment in which it is slideable and to make up for this space and to insure proper sliding I have provided a substantially rectangular guide frame 24 which fits snugly yet freely in the compartment.

100 Associated with the drawer and this frame

is a brace 25 as shown in Figure 2. The adjacent meeting edges of the doors come together in overlapping relation for weatherproof reasons. On the interior of the doors are brackets 26 with which actuating links 27 are pivotally connected. These links are also pivotally connected to the bottom of the tray or to the drawer 18.

It is evident, therefore, that with this arrangement, when the finger ring 23 is grasped and pulled outwardly, the drawer 18 is projected and doors 12 are swung simultaneously to open position. The reverse operation is true when the drawer is retracted or slid back into its protecting compartment 17.

Some of the structural features of the mailbox are as follows. First, I call attention to the box itself, which is of sheet metal, or suitable weather combatting material, vertically elongated, rectangular in shape, provided with a V-shaped water shedding roof and with a pair of suitable shaped front doors. These doors are unique in that they are provided with offset vertical edge flanges hingedly mounted on companion flanges extending outwardly from the side walls of the box so as to allow the doors to telescope into the frontal portion of the box.

Moreover, the overlapping edges at the meeting portions of the doors is unique, along with the angularly disposed channel on the upper edge portion of the doors which fit nicely over the front edges of the roof so as to make a dependable and efficient box.

An equally important and characteristically distinguishable feature of the invention is the horizontal open-front compartment formed in the bottom of the box, to accommodate the drawer, said drawer being designed to accommodate small articles such as letters and coins, leaving the upper and main compartment of the box to take care of larger packages.

This lower compartment is important in that it serves as a housing to receive the slideable mechanism. This slideable mechanism is notable in that it embodies a suitable sliding drawer, a guide frame and bracing means, and the hingedly mounted coin receptacle. Then too, there is the novel arrangement whereby pivoted links provide an operating connection between the drawer and the outwardly opening doors, the protruding handle for operating the drawer, so that as the handle is pulled outwardly the doors are swung open. This simultaneous unified action of parts is desirable and practical indeed.

It is thought that the description taken in connection with the drawings will enable a clear understanding of the invention to be had. Therefore, a more lengthy description is thought unnecessary. Minor changes in shape, size, materials, and arrangement of parts may be resorted to in actual practice if desired.

I claim:

1. In a mailbox structure of the class described, a box, a pair of companion hingedly mounted doors for the open front of said box, a partition in said box forming a bottom compartment, a drawer slideable in said compartment, an operating handle for said drawer extending outwardly through openings in said doors, and operating connections between the drawer and doors. 70

2. In a mailbox structure of the class described, a box, a pair of companion hingedly mounted doors for the open front of said box, a partition in said box forming a bottom compartment, a drawer slideable in said compartment, an operating handle for said drawer extending outwardly through openings in said doors, and operating connections between the drawer and doors, said drawer being provided in one forward corner with a hingedly mounted coin receptacle adapted to facilitate extraction of coins. 85

In testimony whereof I affix my signature.

FRANKLIN GRIMM.
